UNITED STATES PATENT OFFICE.

GEORGE H. LOBER, OF TOLEDO, OHIO.

MACHINE FOR MAKING CONNECTOR TUBES FOR RADIATORS.

Application filed April 8, 1921. Serial No. 459,767.

To all whom it may concern:

Be it known that I, GEORGE H. LOBER, a citizen of the United States, and a resident of Toledo, in the county of Lucas and State 5 of Ohio, have made an Invention Appertaining to Machines for Making Connector Tubes for Radiators; and I do hereby declare the following to be a full, clear, and exact description of the invention, such as will 10 enable others skilled in the art to which it appertains to make and use the same, reference being had to the accompanying drawings, and to the characters of reference marked thereon, which form a part of this 15 specification.

My invention has for its object to provide a machine for making connector tubes, particularly, for radiators. In the construction of radiators the lower water chamber is connected with the jacket of the engine, and in order that the radiator may do its most efficient work, the lower connection should be made at as low a point as possible. I have provided a connector that connects the tubular passageway with an opening formed partly in the bottom and partly in the side of the wall of the lower water chamber of the radiator, and so that the end of the connector has an opening whose edge is such 25 that a portion thereof is located in a plane extending at right angles to the other portion of the edge.

Moreover, it is desirable that the connection with the radiator shall be located at 30 one side of the engine, and consequently, in order to give the desired inclination towards a vertical plane extending through the axis of the crank shaft of the engine, as well as a desired upward slope to permit free flow due 35 to convection or to a power pump, the connector is provided with a body portion which slopes inward as well as upward. This necessitates the formation of a connector that is difficult to shape. By my invention 40 I have provided a machine whereby the connectors may be rapidly formed and may be provided with the necessary flanges for welding or soldering the connector to the bottom and side of the radiator.

The invention may be contained in structures of different forms. To illustrate a 45 practical application of the invention I have selected, for purposes of illustration and description, one or two constructions and dies

whereby the connector may be formed. The 55 machines and dies are illustrated in the accompanying drawings.

Figure 1 of the drawings illustrates a front view of a part of the machine for making the first stampings of the connector, it being understood that the same, or similar plunger presses, may be used for manipulating the dies for completing the connector. Fig. 2 illustrates a sectional view of the upper die taken on the line 2—2 indicated in Fig. 60 1. Fig. 3 illustrates a sectional view of the lower die taken on the line 3—3 indicated in Fig. 1. Fig. 4 shows the shape of the sheet metal before it is placed between the dies illustrated in Figs. 2 and 3. Fig. 5 65 illustrates one of the sheet metal pieces formed, after the dies shown in Figs. 2 and 3 have operated upon it. Fig. 6 illustrates the shape of the piece after it has been trimmed. Fig. 7 illustrates the piece after 70 the sides have been turned preparatory to finishing the connector. Fig. 8 illustrates a top view of the stationary die, the connector being located in position in the die. Fig. 9 illustrates a sectional view taken on the 75 line 9—9 indicated in Fig. 8. Fig. 10 illustrates the upper die that is placed in the plunger press for finishing the connector. Fig. 11 illustrates a side view of the lower die, also shown in Figs. 8 and 9. Fig. 12 80 illustrates the upper and lower dies illustrated in Figs. 10 and 11, when in closed position, that is, when the upper die has finished its operation. Fig. 13 illustrates a side 85 view of the completed connector. Fig. 14 90 illustrates a sectional view taken on the line 14—14 indicated in Fig. 13. Fig. 15 is a top view of the finished connector.

1, Fig. 1, is the frame work of the plunger press, which is provided with the plunger 95 2. A suitable die 3 is connected to the plunger 2 that coacts with the stationary die 4 to produce substantially the semi-form of the connector. Pieces of sheet metal 5, shaped in the manner shown in Fig. 4, are placed on the ring 6, and are elastically held by the rubber cushion means 7. The elastic cushion means 7 is supported on the frame 1 by means of the rod 8, and the ring 6 is connected by means of rods 9 to a plate 10, through which the rod 8 extends. The die 3 strikes first the edge portions of the sheet metal piece 5 that is yieldingly held 105

by the pressure of the rubber cushions 7 between the ring 6 and the face of the die 3, as the die 3 moves down, and shapes the central portion of the sheet 5 to produce substantially the semi-form 11 of the connector. The side edge of the piece 5 is necessarily drawn in by reason of the formation of the semi-form of the connector in the central portion of the flat sheet metal piece 5.

The sheet metal piece 5 is then cut by a suitable shearing die, as shown in Fig. 6, and so as to leave the portion 12 of the connecting flange that is secured to the under-side of the radiator. The portions 13 are then bent roughly substantially to the shape shown in Fig. 7. The sheet metal piece is then placed in a stationary die 14 having a recess 15 conforming to the semi-form of the connector. A cover plate or clamp 16 is then placed across the flange portion 12, and so as to cover the end of the depressed portion 11. The plate is secured by means of a latch or arm 17 and by the lug 18. The plate 25 may be pivoted to the upright 19 by means of the bolt 20. It is provided with an upwardly extending flange 22 for shaping the flange of the connector when the upper die 21 is brought down.

The upper die 21 has a cylindrical channel having flaring edge portions 23 that gather the side portions 13 of the sheet metal when bent roughly into the position shown in Fig. 7, and subsequently draws the side portions 13 into the form of a cylinder. A cylindrical block 27 is placed within the sheet metal piece to form an anvil for the operation of the upper die 21. The block 27 may be provided with a handle 28. The 40 ends of the side portions, that is, the corners of the upper die 21, are provided with beveled surfaces 24 that engage parts of the side portions 13 and guide them towards the flange 22, where they are held by the side 45 25 of the upper die 21, and against which they slide as the side portions 13 of the sheet metal piece are gathered by the die, until

they form the portions 26 of the connecting flange of the connector 28.

The connector is now formed in the shape 50 illustrated in Figs. 13 and 14. The portions 26 may now be united along the line of their contact edges, and also the cylindrically formed portions 13 may likewise be united, as by soldering or brazing or electric welding. If desired, a suitable bead 29 may be formed near the end of the connector, whereby a flexible pipe, such as a rubber pipe, may be connected to the connector in the manner 55 well known in the art.

I claim:

1. In a machine for forming radiator connectors from sheet metal pieces, a stationary die having a recess conforming substantially to the semi-form of the connector, a 65 clamping plate for securing the semi-form of the connector in position and having a flange coacting to shape a portion of the flange of the connector, a block positioned in the connector and forming an anvil, a movable die having a cylindrical recess for gathering edge portions of the sheet metal.

2. In a machine for forming radiator connectors from sheet metal pieces, a stationary die having a recess conforming substantially to the semi-form of the connector, 75 a plate for locking the connector in the stationary die and having a flange coacting to shape a portion of the flange of the connector, a movable die having a channeled portion for gathering side portions of the sheet metal piece over the anvil, and having beveled corners for gathering parts of the sheet metal piece that form a flange portion, and pressing them against the flange of the plate, 80 the side surface of the movable die and the flange of the plate operating to guide the said parts of the connector as the movable die collects the side portions of the connector 85 and presses them against the anvil.

In testimony whereof, I have hereunto signed my name to this specification.

GEORGE H. LOBER.
